UNITED STATES PATENT OFFICE.

JOHN RUMPF, OF NEW MILFORD BOROUGH, NEW JERSEY, ASSIGNOR TO THE SAFETY CAR HEATING & LIGHTING COMPANY, A CORPORATION OF NEW JERSEY.

LIGHTING APPARATUS.

Application filed February 26, 1923. Serial No. 621,122.

To all whom it may concern:

Be it known that I, JOHN RUMPF, a citizen of the United States, and a resident of borough of New Milford, county of Bergen, and State of New Jersey, have invented an Improvement in Lighting Apparatus, of which the following is a specification.

This invention relates to lighting apparatus and with regard to its more specific features to flashing gas lights. One of the objects thereof is to provide a device of the above nature of simple and practical construction, highly dependable in action. Another object is to provide a device of the above nature capable of long-continued service in a satisfactory manner with infrequent attention. Another object is to provide such a device wherein the parts are easily assembled, and in assembled relation are easily accessible in the event of needed replacement or repair. Other objects will be in part obvious or in part pointed out hereinafter.

The invention accordingly consists in the features of construction, combinations of elements and arrangements of parts as will be exemplified in the structure to be hereinafter set forth, and the scope of the application of which will be indicated in the following claims.

In the accompanying drawing in which is shown one of the various possible embodiments of this invention,

Figure 1 is a top plan view;

Figure 2 is a side elevation, certain parts being cut away to more fully disclose the structure;

Figure 3 is an upward plan view in section, the section being taken substantially along the line 3—3 of Fig. 2; and

Figure 4 is a detached segmental view, partly in section, of certain parts shown in the preceding figures.

Similar reference characters refer to similar parts throughout the several views of the drawing.

Referring now to the drawing in detail, with reference first particularly to Figs. 1 and 2, there is shown a casing comprising substantially two parts,—a lower body portion 10 and an upper body portion 11 forming a closure for the top of the body portion 10, and secured thereto as by means of

screws 12 passing through the member 11 and entering a flange 10^a of the member 10. 55 Upon its outer surface the cover or body member 11 is provided with a boss 13 provided with a threaded opening 14 at one end thereof adapted to receive a pipe connection as 15 from any desired source of gas supply. Although any desired illuminating gas may be employed in this apparatus, it is particularly adapted for use in connection with gas stored under pressure, as, for example, Pintsch gas. Connected with the 65 opening 14 in the boss 13 is a passage 16 of smaller diameter from which extend two passages 17 and 18. The passage 18 extends into an upright burner 19 which serves as a pilot light and is provided with a pilot 70 tip 20. The passage 18 is controlled by a needle valve 21 operated by a regulating screw 22 projecting from the side of the boss 13. The passage 17 leads to a chamber 23 where it is controlled by a needle valve 75 24 operated by a regulating screw 25. The chamber 23 is in communication by means of a passage 26 with a recess 27 formed in the lower face of the body member 11, as shown more clearly in Fig. 4. Within this 80 recess 27 is inserted a bushing-like member 28 provided with a passage 29 therethrough. The lower portion of the member 28 projecting from the recess 27 thus forms a substantially annular member 30 which rests snugly 85 up against the lower face of the body member 11 and which serves as a valve seat.

Fitted into a recess 31 in the top portion of the boss 13 is a gas burner 32 positioned adjacent the pilot burner 19. The recess 31 90 below the end of the burner 32 is in communication with the burner tip 33 through the stem of the burner 32 and is also in communication by means of a passage 34 with a recess 35 similar to the recess 27 just described formed in the lower face of the body member 11. Fitted within the recess 35 is a member 36 similar to the member 28 and forming a valve seat 37 similar to the valve seat 30. The openings of the two valve seats 100 30 and 37 open into a chamber 38 formed within the body member 10 and between the body member 10 and the cover member 11. Thus there is provided a passage from the gas supply pipe 15 past the needle valve 105 23 through the valve seat 30 to the chamber

28 and thence through the valve seat 37 to the burner 32.

- Considering now the mounting and operation of the valves which cooperate with 5 the valve seats 30 and 37, depending from the lower face of the cover member 11 are three lugs 39, 40 and 41, substantially in alignment, clearly shown in Fig. 3. Inserted in an opening in the lug 40 and adjustably secured therein by means of screws 42 is a pivot member 43 having pointed ends projecting from either side of the lug 40. Adjustably secured within the lugs 39 and 41 by means of screws 44 are a pair of 10 pointed pivot members 45 and 46, respectively, positioned substantially in line with the member 43. Rotatably held between the pointed end of the member 45 and an end of the member 43 is a shaft 47 to which is secured a transverse rocker arm 48 which is shown more clearly in Fig. 4. At either end of the rocker arm 48 are provided valve members 49 and 50 firmly joined thereto as by solder and in such position as to assure a constant parallel surface between the valve member 49 and the valve seat 37 and between the valve member 50 and the valve seat 30 when the respective valves are closed. The valve members 49 and 50 are provided 25 on their upper surfaces with flat metal disks 52 adapted to cooperate respectively with the valve seats 37 and 30. It will be seen that as the arm 48 rocks with the shaft 47, at one end of its movement the passage 30 from the source of supply to the chamber 38 is closed by the valve 50 and the passage from the chamber 38 to the burner 32 is open. The arm 48 is shown in this position in Fig. 4. At the other end of its rocking 35 movement the opening in the valve seat 37 will be closed by the valve 49 and the opening in the valve seat 30 will be open. In this latter position there is a flow of gas from the source of supply to the chamber 38 while in the position shown in Fig. 4 this flow is cut off and there is a flow of 40 gas from the chamber 38 to the burner 32.
- Referring now again to Fig. 3, secured to a shaft 53 rotatably held between the 45 pointed member 46 and an end of the member 43 is a U-shaped lever member 54, the two arms of which extend opposite to the ends of the arm 48. Adjacent each end of the member 54 and substantially opposite to the adjacent end of the arm 48 are provided openings in which are slidably fitted bushings 55 bearing against the outer ends of which are flat leaf springs 56 secured to the member 54 by means of screws 57. Between the bushings 55 and the adjacent ends of the arm 48 are positioned a pair of struts 58 having cone-pointed ends. It will be seen that since the arm 48 and the member 54 are both movable, being 60 pivoted about substantially the same axis,

the members 58 form a toggle connection therebetween. The struts 58 are of such length that when the arm 48 is substantially in line with the bushings 55 the struts 58 will thrust the bushings 55 outwardly 70 against the action of the springs 56, as is clearly shown in Figs. 2 and 3. When the arm 48 is not in line with the bushings 55 the struts 58 assume positions such as shown in Fig. 4, the bushings 55 being 75 thrust inwardly by the springs 56.

Now, assuming that the arm 48, the lever 54 and the struts 58 are in the position shown in Fig. 4, the inlet valve 50 being closed and the outlet valve 49 being open, 80 a counter-clockwise rotation of the lever 54 viewed in Fig. 2 moving the right-hand side thereof in an upwardly direction and the left-hand side thereof downwardly brings the struts 58 into line with the arm 85 48. This action as above described thrusts the bushings 55 outwardly and distorts the springs 56. As soon as the lever 54 is rotated sufficiently to carry the struts 58 past this central position, namely, in line with 90 the arm 48, the energy in the distorted springs 56 will suddenly be released snapping the arm 48 quickly to a position opposite to that shown in Fig. 4, since the arm 48 is freely pivoted between the pointed members 43 and 45. In this position, as above described, the valve 49 is closed and the valve 50 is open permitting flow of gas from the source of supply to the chamber 38 and cutting off flow from the chamber 100 38 to the burner 32. A clockwise rotation of the lever 54 about its axis will now have the reverse effect and the valves will be snapped back to the position shown in Fig. 4. It is to be noted that the movement 105 of the arm 48 and consequently the opening and closing of the valves will be almost instantaneous regardless of the speed of movement of the lever 54 about its axis. Also, upon movement of the arm 48 the 110 opening and closing of the respective valves occurs substantially simultaneously.

Referring now to Fig. 2, the interior of the casing 10 is provided with a partition 60 forming a portion of the lower wall of 115 the chamber 38. The partition 60 is provided with an opening 61 in which is positioned a diaphragm 62, the edges of which are clamped between the partition 60 and a ring 63 secured thereto by means of 120 screws 64. The central portion of the diaphragm 62 is clamped between the two plates 65 and 66 by means of a clamping bolt 67 provided with clamping nuts 67^a and 67^b. The ring 63 is provided with a depending portion 68 between which and the lower clamping plate 66 is supported a compression spring 69. Secured to the upper end of the clamping bolt 67 is an arm 70 which projects upwardly therefrom and is 130

pivottally connected to a lug 71 secured to the lever 54 as is shown in Fig. 3. The diaphragm 62 is thus exposed to gas pressure within the chamber 38 and the effect 5 of the gas pressure thereon is opposed by the compression spring 69. Through the arm 70 the lever 54 is caused to rotate about its axis in response to movements of the diaphragm 62. A pressure of gas in the 10 chamber 38 greater than the force exerted by the spring 69 will cause a downward movement of the diaphragm 62 and through the arm 70 a clockwise rotation of the lever 54 about its axis as viewed in Fig. 2. Conversely, a pressure within the chamber 38 15 less than that exerted by the spring 69 will result in a counter-clockwise rotation of the lever 54. The effect of such rotation of the lever 54 upon the arm 48 and the valves 49 and 50 is as has been described 20 above.

In operation, a source of gas supply, preferably Pintsch gas as above mentioned, is connected with the apparatus as by means 25 of a pipe connection 15. Gas will now flow through the passage 18 to the pilot burner 19 and upon being ignited the pilot light will continue to burn steadily without interruption. There being little or no gas 30 pressure within the chamber 38 the inlet valve 50 will be in open position and the outlet valve 49 will be in closed position. Now, as the gas enters the chamber 38 it builds up pressure therein and the diaphragm 62 commences to move downwardly 35 against the pressure of the spring 69, rotating the lever 54 in a clockwise direction, as above described, until the struts 58 have passed their central position. Thereupon 40 the arm 48 is quickly rotated in a counter-clockwise direction by the energy of the distorted springs 56 to the opposite end of its travel closing the inlet valve 50 and opening the outlet valve 49. The entrance 45 of gas to the chamber 38 is now cut off and there is a flow of gas from the chamber 38 to the burner 32 where it is ignited by the pilot light. This outward flow of gas causes a reduction of pressure within 50 the chamber 38 and the spring 69 urges the diaphragm 62 upwardly again causing a counter-clockwise rotation of the lever 54 until the arm 48 is again snapped over closing the outlet valve 49 again and opening 55 the valve 50. The flow of gas to the burner 32 now being cut off, the light goes out. Pressure now begins to build up once more in the chamber 38 and the cycle is repeated.

There is thus brought about an intermittent flashing of the light. The length of the dark period is determined by the adjustment of the screw valve 25 regulating the rate at which the gas enters the chamber 38. The length of the light period is determined by adjustment of the burner 32

to regulate the rate of flow of gas therethrough. Also by adjustment of the clamping bolt 67 with respect to the diaphragm 62 by means of the nuts 67^a and 67^b the connection between the diaphragm and the lever 54 may be adjusted. A lengthening of this connection raising the lever 54 with respect to the diaphragm 62 will cause the arm 48 to snap to closing position of the valve 49 upon a shorter movement of the diaphragm 62, and the length of the light period is thus correspondingly shortened. The apparatus as a whole is highly sensitive and adapted for accurate operation, the pivoted points for the lever 54 and the arm 48 substantially doing away with friction. Furthermore, the parts are particularly easily accessible. The valve mechanism is mounted upon the cover member 11 and by simply loosening the diaphragm 62 and removing the cover 11 from the casing 10 the entire mechanism may be withdrawn from the casing 10 and is exposed for convenient access.

It will thus be seen that there is herein provided an apparatus which embodies the features of this invention, which apparatus in its action attains the various objects of the invention and that the same is well adapted to meet the requirements of practical use.

As various possible embodiments may be made of this invention and as many changes might be made in the embodiment above set forth, it is to be understood that all matter hereinbefore set forth or shown in the accompanying drawing is to be interpreted as illustrative and not in a limiting sense.

I claim as my invention:

1. In a device of the class described, in combination, a pressure chamber, a fluid passage thereto, a valve member pivotally mounted to swing into and out of position to control said passage, a diaphragm responsive to fluid pressure within said chamber, a member connected to move with said diaphragm, a spring mounted upon said member, and means interposed between said member and said valve adapted upon movement of the former to store energy in said spring and upon further movement in the same direction to apply said energy to move said valve.

2. In a device of the class described, in combination, a pressure chamber, a fluid passage thereto, a valve mounted to move into and out of position to control said passage, a diaphragm responsive to fluid pressure within said chamber, a member connected to move with said diaphragm, a spring mounted upon said member, and a strut loosely interposed between said spring and said valve adapted upon movement of said member to distort said spring and upon

further movement of said member in the same direction to permit said spring to move said valve.

3. In a device of the class described, in combination, a pressure chamber, a fluid passage thereto, a valve member pivotally mounted to swing into and out of position to control said passage, a diaphragm responsive to fluid pressure within said chamber, a member connected to move with said diaphragm, a leaf spring mounted upon said member, and means interposed between said spring and said valve adapted upon movement of said member to distort said spring and adapted upon further movement of said member in the same direction to permit said spring to move said valve.

4. In a device of the class described, in combination, a pressure chamber, a fluid passage thereto, a pivoted member, a valve connected to said pivoted member adapted to control said passage, a diaphragm responsive to fluid pressure within said chamber, a second pivoted member connected to swing about its pivot in response to movements of said diaphragm, and means interposed between said two pivoted members adapted upon predetermined movement of the second about its pivot in response to a movement of said diaphragm to snap the first about its pivot to move said valve.

5. In a device of the class described, in combination, a pressure chamber, an inlet passage thereto, an outlet passage therefrom, a pair of valves adapted respectively to control said passages, a pivoted member adapted upon swinging about its pivot to open one of said valves and close the other, a diaphragm responsive to fluid pressure within said chamber, a second pivoted member connected to swing about its pivot in response to movements of said diaphragm, and means interposed between said two pivoted members adapted upon predetermined movement of the second about its pivot in response to a movement of said diaphragm to snap the first about its pivot to move said valves.

6. In a device of the class described, in combination, a pressure chamber, an inlet passage thereto, an outlet passage therefrom, a pair of valves adapted respectively to control said passages, a pivoted member having a pair of arms adapted respectively upon swinging about said pivot to open one of said valves and close the other, a diaphragm responsive to fluid pressure within said chamber, a second pivoted member having a pair of arms one on either side of its pivot respectively extending adjacent said two arms of said first pivoted member and connected to swing about its pivot in response to movements of said diaphragm, and means interposed between each of said arms of said second pivoted member and

the adjacent arm of said first pivoted member adapted upon predetermined swinging of said second pivoted member in response to a movement of said diaphragm to snap said first pivoted member about its pivot to move said valves.

7. In a device of the class described, in combination, a pressure chamber, an inlet passage thereto, an outlet passage therefrom, a pair of valves adapted respectively to control said two passages, a member pivoted adjacent its center and connected to said two valves adjacent its respective ends adapted upon swinging about its pivot to open one of said valves and close the other, a diaphragm responsive to fluid pressure within said chamber, a substantially U-shaped member pivoted between its two arms, said two arms thereof extending respectively adjacent the two ends of said first pivoted member, said U-shaped member being connected to swing about its pivot in response to movements of said diaphragm, and a connection between each of said two arms of said U-shaped member and the adjacent end of said first pivoted member adapted upon predetermined swinging of said U-shaped member to snap said first pivoted member about its pivot to move said valves.

8. In a device of the class described, in combination, a pressure chamber, a fluid passage thereto, a valve controlling said fluid passage, a diaphragm responsive to fluid pressure within said chamber, a pivoted member connected to move in response to movements of said diaphragm, means connecting said pivoted member and said valve adapted upon predetermined movement of the former to actuate the latter, and means for adjusting said connection between said pivoted member and said diaphragm to vary the amount of movement of said diaphragm required to move said pivoted member to actuate said valve.

9. In a device of the class described, in combination, a hollow casing member, a cover member removably secured to said casing closing one side thereof and forming therewith a gas chamber, a source of gas supply, a gas burner mounted upon said cover member, a pair of passages through said cover adapted to connect said chamber with said source of supply and said burner respectively, a pair of valves mounted upon the inner side of said cover within said chamber and respectively controlling said two passages, and means within said chamber responsive to gas pressure therein adapted intermittently to move said valves together to open one and close the other.

10. In a device of the class described, in combination, a casing member, a cover member removably secured to said casing and closing one side thereof, a diaphragm clos-

- ing the opposite side of said casing, a source 5 of gas supply, a gas burner, a pair of passages through said cover member adapted respectively to connect the interior of said casing with said gas supply and said burner, a pair of valves mounted upon the inner side of said cover member and respectively controlling said two passages, a device mounted upon the inner side of said cover member adapted upon predetermined movement to open one of said valves and close the other, and means connecting said device and said diaphragm to make the former responsive to movements of the latter.
- 10 15 11. In a device of the class described, in combination, a casing member comprising a chamber, a casing member forming a closure for one side of said chamber and removably secured to said first casing member, a source of gas supply, a gas burner mounted upon said second casing member, a gas passage connecting said source of supply and said chamber, a gas passage connecting
- 20 25 30 35 40 45 said chamber and said burner, and valve mechanism mounted upon said second casing member controlling said two passages.
12. In a device of the class described, in combination, a casing member comprising a chamber, a casing member forming a closure for one side of said chamber and removably secured to said first casing member, a source of gas supply, a gas burner mounted upon said second casing member, a gas passage connecting said source of supply and said chamber, a gas passage connecting said chamber and said burner, valve mechanism mounted upon said second casing member controlling said two passages, and a diaphragm mounted within said first casing member responsive to gas pressure within said chamber and connected to actuate said valve mechanism.

In testimony whereof, I have signed my name to this specification this 13 day of February, 1923.

JOHN RUMPF.
